CATAMENIAL APPLIANCE

Ina B. Hammond, Danbury, Conn.

Application January 8, 1934, Serial No. 705,810

3 Claims.

(Cl. 128—290)

This invention relates to catamenial appliances and more particularly to sanitary shields for use in conjunction with catamenial bandages, napkins or the like.

Among the objects of my invention may be noted the provision of a sanitary shield peculiarly adapted for feminine hygiene; the provision of a sanitary shield which requires no pins or fasteners of any kind during wear; the provision of a sanitary shield which may be readily associated with a sanitary napkin and which derives its support from the napkin in the normal use thereof; the provision of a sanitary shield for association with a sanitary napkin, which when properly associated therewith may be removed from and thereafter applied to the body without detaching the shield from the napkin; the provision of a sanitary shield which is form fitting and, when used with a sanitary napkin, forms a support for the napkin and at the same time assures comfort to the wearer; the provision of a sanitary shield which is stainless and which contains deodorizing properties; and the provision of a sanitary shield which is simple in manufacture, durable in use, and well able to fulfill the ends for which it is intended.

Other objects will be in part obvious from the annexed drawing and in part indicated from the following analysis of this invention, in which reference is made to the accompanying drawing illustrating an embodiment of my idea, in which—

Fig. 1 is a perspective view of a sanitary shield in accordance with the present invention associated with a sanitary napkin, with the napkin and shield operatively supported from a belt or the like as in use.

Fig. 2 is an under face view of the shield as illustrated in Fig. 1;

Fig. 3 is a section along lines 3—3 of Fig. 2; and

Fig. 4 is a section through the shield and napkin, which illustrates the shape assumed by the shield in use.

Referring to the drawing, and particularly to Fig. 1, 10 designates a belt adapted to extend about the waist or hips of the wearer and provided with front and rear tabs 11 to which the napkin, which may comprise an absorbent pad 12 and gauze covering 13, is secured as by pins or otherwise. It will be understood that the belt or the napkin forms per se no part of the present invention and may be of conventional type and construction. According to the present invention, I provide for association with the napkin a shield of moisture-proof and water-proof material, such

shield serving, upon excess fluid absorption by the pad 12, to protect the clothing of the wearer from stains or the like.

By reference to Fig. 2, the shield is composed of a sheet or the like which comprises an elongated body portion 15, having its sides which extend in the direction of its length arranged parallel or substantially so, and tabs 16 extending from the ends of the body portion and in the direction of its length. The parallel sides of the body portion merge into the tabs 16 through a gradual curve 17. Such configuration of the shield eliminates bulky or obtruding corners which might otherwise show through outer clothing and at the same time adds comfort to the wearer. The body portion 15 is made of suitable water-proof and moisture-proof material, and among such materials may be mentioned sheeted rubber, fabric frictioned or coated with rubber, or any other material coated or treated with rubber. The tabs 16 are preferably less elastic than the body portion and may be formed of pure gum. Where reinforcement of the tabs is desired, the gum tabs may be reinforced with fabric, or provided with fabric or metal inserts.

The body portion is provided along its parallel sides with molded edge or bead portions 18 which may, like tabs 16, be of less elastic material than the material from which the body portion is constituted, and advantageously can be of pure gum. The said edge 18 and the tabs are joined to the body portion in a single operation as by pressing in a mold. The resulting structure is integral and thus overcomes the disadvantages incident to the use of cement which deteriorates with washing, and of stitching which has been found to retain stains and to be generally unsanitary.

Considering now the manner of attaching the shield to the napkin, the tabs 16 are each provided with a plurality of parallel slots 20 which are arranged transversely of the length of the shield. By reference to Fig. 1, the napkin covering 13, as is conventional, is substantially longer than the pad 12, the ends extending forwardly and rearwardly of said pad to the tabs 11 on supporting belt 10. By the provision of the tabs 16 having slots 20 as illustrated, I am able to join the shield to the napkin by threading the ends of wrapper or cover 13 of the pad through the slots 20. As will be seen by reference to Fig. 2, the slots 20 of each tab 16 may be of varying lengths, thus to provide a selection of a slot or slots best suited to the thickness of the stranded or bunched ends of the napkin covering 13. Further, the said ends may be run through adjacent slots,

alternate slots, or substantially spaced slots as desired, thus to give within reasonable limits an adjustment which may be necessary for the comfort of the wearer.

5 It will be evident that the bunched ends of the fabric covering 13 are gripped by the edges of slots 20. Such a relation is desirable, for it permits that the shield be held in a desired adjusted position along the length of the napkin. In 10 point of fact, I propose that the edges of slots 20, by suitable proportioning of the length of the slots, shall grip the fabric of the napkin covering sufficiently so that as tension is exerted on both ends of the napkin, due to snugly fitting the napkin to the body and connecting to the belt 10, the shield shall also be put under tension. By reason of the tabs 16 and edges 18 being of less elastic material than the body portion 15 of the shield, and by reason further of the slots 20 being disposed in the relatively less elastic tab portions 15 and transversely of the direction of pull, any such tensioning causes the shield to elongate along its longitudinal center line, with the edge portions of the tabs 16 and the molded edges 18 resisting such elongation, with the result that the shield is cradled upwardly. The edges 18 are accordingly drawn tight to the sides of the pad 12 of the napkin, with the shield thus providing a cradle or concavity snugly fitted about the napkin. By reference to Fig. 4, it will be seen that as 20 the napkin is placed in position on the wearer, the napkin will adjust itself to the figure, with the sides of the cradled shield extending upwardly along the sides of the napkin, thereby to protect the body and clothing from side overflow, and at the same time protecting against chafing and irritation, as would normally be caused by the body coming in contact with the sides of the napkin, especially when the napkin has become caked 25 due to heat of the body or inability to make frequent change. Instead, the soft rubber sides of the shield are contacted by the flesh and there exists no possibility of chafing. Further, the resiliency and lightness of the shield are such as to make the wearer unaware of its presence.

40 Although I have illustrated and described above slots 20 of longitudinal form, apertures of other forms or shapes could be utilized. Thus a plurality of spaced apertures of circular or elliptical shape through which the fabric ends of the napkin covering 13 are threaded could be substituted for the slots 20 as shown.

45 Advantageously, the shield during its manufacture is treated for the purpose of rendering it stainless or substantially so, by the addition of certain chemicals added to the rubber during its compounding, all as known in the prior art in connection with rubber goods such as surgeons' gloves and the like. It is advantageous also that the rubber making up the shield be deodorized by adding to the rubber during compounding certain deodorizing ingredients, which obscure the natural odor of the rubber while at the same time impart a scent to the rubber of such nature as to counteract offensive odor caused by close personal contact or otherwise. Among such ingredients as known in the prior art, the use of essential oils, generally synthetic, of an organic character has been found satisfactory. It will of course be understood that pigments are added to the rubber,

5 and the shield as commercially produced will have a white or flesh color.

10 The shield when associated with a sanitary napkin as aforesaid requires no extraneous fastening means, such as pins, buttons or the like. Its connection with the napkin is such that the napkin and shield may be removed from the body without detaching the shield from the napkin, with the shield retaining its original position thereon for reapplication to the body.

15 Without further analysis the foregoing will so fully reveal the gist of this invention that others can by applying current knowledge readily adapt it for various applications without omitting certain features that, from the standpoint of the prior art, fairly constitute essential characteristics of the generic or specific aspects of this invention and therefore such adaptations should and are intended to be comprehended within the meaning and range of equivalency of the following claims.

20 I claim:

25 1. A sanitary shield comprising an elongated elastic rubber sheet having molded tabs at the ends thereof and the tabs being each provided with a series of apertures through which may be threaded the ends of a sanitary napkin, the edges of the sheet which extend in the direction of its length being merged into said tabs, with said tabs and edges being so constituted as to offer 30 greater resistance to tension than the body portion of the sheet, and said apertures being disposed transversely of the length of the sheet whereby tension on the tabs causes elongation of the shield along its longitudinal center line 35 relative to the molded edges of the sheet, with the shield assuming a concave shape in cross section.

40 2. A sanitary shield comprising an elongated elastic rubber sheet having molded tabs at the ends thereof, the tabs being each provided with a series of apertures through which may be threaded the ends of a sanitary napkin, the sheet being provided with molded edges extending in the direction of its length and merging into said 45 tabs, said tabs and edges being so constituted as to offer greater resistance to tension than the body portion of the sheet, and said apertures being disposed transversely of the length of the sheet whereby tension on the tabs causes elongation 50 of the shield along its longitudinal center line relative to the molded edges of the sheet, with the shield assuming a concave shape in cross section.

55 3. A shield for use in association with a sanitary napkin, the shield being composed of a deodorized and scented elastic rubber sheet, said sheet being elongated and provided with molded longitudinal edges which merge into end tabs, said tabs being each provided with a series of 60 parallel slots arranged transversely of the length of the sheet and through which the ends of the napkin may be threaded, the disposition of the slots and their relation to said tabs and edges being such that as tension is exerted on the tabs 65 the shield is elongated along its longitudinal center line relative to the molded edges, whereby the shield assumes a concave shape in cross section.

INA B. HAMMOND.
